UNITED STATES PATENT OFFICE.

CHARLES C. WORTHINGTON, OF IRVINGTON, NEW YORK.

DESIGN FOR A PUMP-CASING.

SPECIFICATION forming part of Design No. 34,514, dated May 14, 1901.

Application filed August 26, 1898. Serial No. 689,614. Term of patent 14 years.

To all whom it may concern:

Be it known that I, CHARLES C. WORTHINGTON, a citizen of the United States, residing at Irvington, county of Westchester, and State of New York, have invented and produced a certain new and original Design for Pump-Casings, fully described and represented in the following specification and the accompanying drawings, forming a part of the same.

This invention relates to a design for the casing of a pump, the especial object of the invention being the production of a new and original design for vertical pumps of that particular class known as "sinking-pumps" and used in deep-mining operations, where a pump of very small cross-section is desired.

The invention consists in the peculiar shape or configuration of a pump-casing, substantially as shown in the accompanying drawings, in which—

Figure 1 is a front view of the pump-casing embodying the design, and Fig. 2 is a side view of the same.

The leading feature of the design is the peculiar arrangement of the pump-cylinders A, with the projecting portions B and C of the casing on opposite sides of the pump extending over the two cylinders and arranged in different planes transversely to the pump

or horizontally and out of line with each other longitudinally of the pump or vertically, so that these projecting portions are arranged circumferentially about the cylinder, but in different planes, and with pipes D 35 E extending longitudinally of the cylinders or vertically and alongside the portion of the cylinders about which the projecting portions B C of the casing do not extend, with one of the pipes between the cylinders, substantially as shown.

In the drawings the opposite ends of the pump are shown as formed separately and secured together by flanges 10 and bolts 11, and end flanges 12 on the casing are shown for 45 securing a steam end or other motor mechanism, as usual in pump-casings, and shown as provided with the usual exterior stuffing-boxes.

What I claim is—

The design for a pump-casing, substantially as shown and described.

In testimony whereof I have hereunto set my hand in the presence of two subscribing witnesses.

CHARLES C. WORTHINGTON.

Witnesses:

LOUIS R. ALBERGER,
GEO. M. VAN DOORN.
